SUPPORT STAND FOR A HANGING SEAT OR SIMILAR ARTICLE

Phillip A. Gass, 241 S. 89th St., Omaha, Nebr. 68114

Filed Apr. 7, 1972, Ser. No. 242,297

Term of patent 14 years

Int. Cl. D6—06

U.S. Cl. D6—29

FIG. 1

FIG. 2

FIG. 3

FIG. 4

FIG. 5

FIG. 1 is a perspective view of a support stand for a hanging seat or similar article showing my new design;

FIG. 2 is a side elevational view thereof;

FIG. 3 is a top plan view thereof;

FIG. 4 is a rear elevational view thereof;

FIG. 5 is a front elevational view thereof.

I claim:

The ornamental design for a support stand for a hanging seat or similar article, substantially as shown.
